UNITED STATES PATENT OFFICE.

WILLARD C. BRINTON, OF NEW YORK, N. Y.

CURVE RECORD SYSTEM.

Application filed September 26, 1917. Serial No. 193,391.

To all whom it may concern:

Be it known that I, WILLARD C. BRINTON, a citizen of the United States of America, and a resident of New York, county and

5 State of New York, have invented certain new and useful Improvements in Curve Record Systems, of which the following is a specification, reference being had to the accompanying drawings, forming a part 10 thereof.

My invention relates to methods and equipment for the graphic presentation of facts, and has special reference to graphic records utilized in factory and business management, and known as graphic control 15 cards.

One object of my invention is to provide particularly simple and effective record sheets or cards and methods of combining, 20 comparing and utilizing them, whereby business organizations of various kinds and for various purposes, may be efficiently and economically administered or managed.

The various objects and advantages of my 25 invention will be set forth more in detail hereinafter, and illustrative examples will be chosen in order to make the operation of the invention and the preferred arrangement of the appliances apparent.

30 Referring to the drawings:

Figure 1 is a plan view of a plurality of graphic control cards, which constitute embodiments of my invention, overlapped for the purposes of comparison.

35 The same cards are shown combined in another way in Figure 2.

Figure 3 shows a pair of cards for a different purpose, superposed for the purposes of comparison, the top card being partially 40 broken away to illustrate the one beneath.

Figure 4 shows the lower part of the under card of Figure 3.

Figure 5 is a sectional elevation of a light 45 box which I prefer to use in comparing graphic control cards.

Figures 6, 7 and 8 show small portions of modified cards which also embody my invention.

50 Referring first to Figures 1 and 2, I have here shown the three cards which represent the sales made by a salesman designated W, from the beginning of the year 1914, up to

the 8th month of the year 1916. The cards for the years 1914, 1915, and 1916, are designated respectively, 10, 11 and 12 and are 55 similar to each other.

Referring to the card 10,— 13 designates the base line, and 14 a plurality of major coordinates parallel therewith. These are drawn at a predetermined distance apart 60 and preferably at a convenient unit distance such as one inch, and they are preferably heavier than the intermediate coordinate lines or of a contrasting color so that they are readily distinguished therefrom. 65

Between the major coordinates 14 are intermediate or subdivisional coordinates 15 parallel to the coordinates 14, and a plurality of coordinate lines 16 at right angles to the base. 70

The coordinate field is confined to the lower right-hand portion of the card area, a narrow margin 17 being left at the right hand edge and at the bottom, and a wide margin being left at the top and at the left 75 side.

The length of the base line in the example chosen represents a definite time which in this case is one year. The coordinates 16 divide the base into twelve equal parts which 80 represent months. In the margin 18 at the left sides are scales 19, 20 representing values. In the example illustrated one of the scales is laid out with \$20,000 equal to one space between subdivision coordinates 15. The 85 other scale 20 which may be made in red ink is laid out with one space equal to \$40,000. On the curve sheet are three curves 21, 22 and 23. The curve 21 is laid out by the scale 19 and is preferably drawn with the same color ink as that employed in making the figures of the scale 19.

The curve 21 represents actual values of the sales made by the salesman W, for the successive months of the year 1914. This 95 curve does not go to zero, or to the left hand side line of the coordinate area, because it may be assumed that the salesman started to work Jan. 1st and the first month's total was obtained Feb. 1st, or at the end 100 of the first month. For this reason the left hand line is marked 12 at the bottom and the next vertical line 1. The curve 21 shows at a glance what the salesman is doing and

when the best seasons for business were. The curve 22 is cumulative curve and it is laid out by the scale 20. It may for example be made in red ink corresponding to the figures of the scale. The points of the curve 22 are obtained by adding the sales month by month, so that the end of the curve 22 indicates the cumulative sales for the year.

Assuming that the salesman has been at work for some time so that records are available for a year past, the curve 23 is produced by plotting the total sales for the preceding twelve months, at the end of each month. The curves 22 and 23 of course meet at the end of one year.

These three curves may together be referred to as a "Z-chart," as two of them spaced apart and in substantially horizontal directions are joined by the third which runs from the right hand end of the upper one to the left hand end of the two first mentioned lines, and therefore assumes the characteristics of a capital letter Z.

By referring to Figure 2 where the curves for the two years and part of the third year are available, it is evident that the curves 22 and 23 for the year 1916 constantly serve as a means for estimating the total sales for the year before the year is completed, because they always meet at the end of the year.

The curve 23 may, if desired, be drawn in a third color and columns of figures designated 24—25—26 are located at the top of the card in the margin, each amount being opposite one of the vertical coordinates 16, and giving the value of the sales corresponding to the month represented by its coordinate.

The scale selected for the total and cumulative curves is different from that used for the monthly sales curve. This is not necessary but is desirable because it brings the curves closer together where they can be more easily compared.

The column of figures 24 is marked "Month" and is preferably laid out in black ink corresponding to the curve 21 and the scale column 19. Furthermore, it is the bottom column of the three so that it corresponds in relative position to the lower curve to which it relates. In like manner the middle and top columns 25 and 26 correspond to the middle and top curves.

In the right hand margin near the bottom of the card is an arrow line 27 which is adapted to have the head put on to indicate the desired fluctuation of the curves 21, 22, 23. Of course in the example represented the desired fluctuation is upward. As explained in connection with Figure 3, the arrow 40 is left incomplete because no particular change of the curve is desirable except relative to some other curve. For example, it is often desirable to have the payroll in-

creased if the value of sales increases to a greater extent.

Figure 1 shows how to compare the actual sales for the three years, particularly with reference to any given month or season of the year. Attention is directed to the fact that the narrow margins at the bottom permit the curves to be brought close together, and furthermore, the heavy, major coordinate lines 14 serve as a guide to the eye. When the cards are overlapped as shown in Figure 1, it is evident that the curve for the remainder of the year 1916 can readily be estimated.

In order to get a general line on the salesman's work to ascertain particularly whether his work is improving or whether he is producing poorer results, the three cards are preferably lapped as shown in Figure 2. The narrow margins at the right-hand of the cards enable them to be brought close together so that they form practically a continuous curve. In the arrangement of Figure 2 the curves are not only joined but the columns of figures at the top of the card are united into practically continuous columns, and the one set of scales visible at the left applies to all the cards. The narrow margin may be omitted entirely if desired, thus enabling the cards to be lapped to produce a continuous coordinate field. The year to which the record applies is indicated both in the upper right and lower left-hand corners of the cards to make them visible when the cards are overlapped in either of the ways above described.

The cards are preferably made of translucent material such as a high-grade ledger paper, celluloid or the like, in order that they may be superposed for comparison, for instance, the cards for the years 1914 and 1915, might be directly superposed, the coordinate areas being correspondingly located on each. They may conveniently be compared by placing them on the translucent top of a light box as shown in Figure 5 and as hereinafter explained.

In order to illustrate another feature of my invention graphically, I have shown unlike cards superposed in Figure 3; 30 is the under card and 31 the superposed card. The card 30, a portion of which is also shown in Figure 4, is a factory sales card and has vertical coordinate lines 32 corresponding to the line 16 of Figure 1 and designating the year by months. The coordinate area is disposed at the lower right hand portion of the sheet and the horizontal coordinate lines 33 between the major lines 34 may be spaced at any suitable distance apart, dependent on the scale to be utilized. The major lines 34 however correspond to the major lines 14 and are preferably at a unitary distance apart, preferably one inch.

The sheet 31 has a coordinate field of the

same size and similarly disposed, so that when the card edges are brought together the areas are registered. Furthermore, the card 31 has major coordinates 34 which exactly register with those of the card 30.

The card 31 however, has vertical coordinates 35 which divide the base line 36 into fifty-two divisions representing weeks and also horizontal subdivision coordinates 37.

- 10 The card 31 is thus particularly adapted to have a pay roll plotted on it, the pay roll being made up weekly, whereas the card 30 may have a monthly sales factory record. The advantage of arranging and laying out 15 the cards as above described, is apparent from the fact that the two items which it is highly desirable to compare, may be directly compared by superposing the cards even though the cards have their coordinates 20 laid out in a different manner.

The curve 38 is plotted to represent the weekly payroll, while the curve 39 represents the factory sales.

- There is another condition which must 25 be taken into consideration in order that the best comparative results may be secured, and that is the selection of scales representing values which are not necessarily the same for the two cards, but which are so 30 chosen as to make the curve substantially center on a predetermined major coordinate or at a predetermined distance from the base. I prefer that the scale shall be selected as an example shown in Figure 3, 35 to make the curve center on the one inch line, that is to say, the first major coordinate above the base.

- It is not essential, and in some cases not 40 desirable to superpose the cards with their edges in register, the curves being brought into approximate register by keeping the base lines, or the average height curve lines, such as the one-inch lines, together and laterally sliding the cards into suitable relation.

- 45 For example, referring to Figures 3 and 4, it is apparent that the short marks designated 50 and representing the beginning and end of the months will not coincide with the coordinates 35 representing weeks except when the month begins at the beginning of a week. The month lines will be different for different years and in comparing curves the short month marks on the weekly card 55 such as 31, are brought into register with the month marks or month coordinate lines, such as 32 on the monthly card 30.

- If the cards are superposed with the months in register and the curves do not 60 even approximately correspond in position while their shapes are similar in general showing that they are related, (this is the case illustrated in Figure 3) the difference between peaks clearly indicates the lag or 65 lead between the curves. The factory sales

curve lags about three months behind the factory payroll curve in Figure 3.

Having ascertained this relation the curves may be brought into register by moving the card 30 to the left until the peaks 70 approximately correspond in position. In this relation the payroll curve may for example be examined to determine a discrepancy relative to the sales and a careful check is available at all times.

If the lead or lag from year to year varies materially, steps may be taken to correct it by hastening deliveries, etc.

If curves are compared by merely plotting 80 on the same sheet as heretofore, the coordinate layout is likely to be unsuitable for at least one of the curves and comparison of the curves is difficult, whereas, according to my invention, each curve has 85 its own coordinate field which is chosen to 90 suit the values to be plotted.

In plotting the curve, the value representing in round numbers the average height 95 of the curve is first determined approximately, then a scale is chosen, which brings 100 the average height at the one inch line of the sheet, the selection of the particular sheet or card being such that the minor transverse coordinates divide the space conveniently with reference to the average 105 height value. For example, if the average height value is found to be 80,000 the sheet or card shown in Figure 6 may be chosen because 80,000 is readily divided into 110 fourths.

Each of the sheets is provided with a headless arrow in the right hand margin near the bottom which may be completed as already explained. The headless arrow 40 of the pay roll sheet will however, be left 105 uncompleted because it may be desirable to increase the pay roll at one time and decrease it at another. The arrow 41 of sheet 30 will point upward because it is desired 110 of course to increase the factory sales.

In Figures 6, 7 and 8 I have illustrated 115 portions of additional sheets 42-43 and 44. These have correspondingly located and spaced major coordinates 45. They furthermore have correspondingly located vertical coordinates 46 but the intermediate or subdivision lines for card 42 divide the space between major coordinates into four parts, those of card 43 into five parts and those of card 44 into six parts. Other cards may 120 of course be provided dividing the spaces into still smaller subdivisions.

From the example already set forth the 125 particular utility of this arrangement will be apparent.

In utilizing the cards, I prefer to employ a scale such as a triangular scale, laid out in inches, with subdivisions on its various faces, showing various fractions of an inch. For instance, one surface may divide the 130

5 inches into fourths, another into fifths, one into sixths, etc., making the intermediate or subdivisions correspond with the subdivisions between the major coordinates of the cards. On the scale each of the subdivisions above referred to is still further subdivided into tenths making it very easy to locate points on the curve being plotted.

10 In comparing the cards by the method of superposing as above described, I prefer to utilize a box or frame 52 having a glass top composed of two spaced panes 51 and 51^a, and containing an electric light 53, or some other suitable means of illumination, so that 15 the cards may be laid on the top glass with the light shining through them. By using two spaced panes of glass the outer one is relatively cool and all danger of injuring the cards is avoided. Amber glass may advantageously be used for the outer pane as 20 the contrast between the black lines of the curve sheet and the background is made sharper. A reflector may preferably be placed in the box behind the light or the interior walls of the box suitably whitened.

25 The cards may of course be spread on a table or turned over in a file, but it is also possible in many cases to make a very interesting presentation of recorded facts by 30 throwing a reflection of the curves and all the matter found on the sheet, onto a screen by means of a suitable stereopticon or reflector machine.

35 Continuous Z charts may be made up on a single sheet to have somewhat the appearance of Figure 2 with a series of cumulative curves meeting the total curve at various points. This is particularly interesting as showing the total annual variations.

40 The total curve may of course be based on any predetermined total other than one year if desired. For example, it may be based on a six months period and if the curve sheet is made up for one year, two cumulative 45 curves will appear, one joining the total curve at the end and the other at a convenient point.

50 On the actual value curves, attention is directed to the fact that the points where the curves cross the vertical coordinates truly 55 represent the values for the month so that it may be found desirable to use a series of dots or points representing the actual value for each month which is represented by a single vertical coordinate line instead of connecting the points by straight lines which do not accurately represent values between the month lines.

60 In order to make a curve complete as shown in Figures 6 and 7, I prefer to number the vertical coordinates on the base line 12, 1, 2, 3, 4, 5, 6, 7, 8, 9, 10, 11, 12, the first 12 representing the last month of the preceding year.

65 Attention is particularly directed to the

fact that the total curve which forms a part of the Z chart shows the difference between the current month of any one year and the same month of the preceding year by its direction. For example, if the total curve 70 moves from one month to the next in an upward direction, that indicates that the current month is better than the preceding month of the previous year, whereas if the total curve drops that means that the present 75 month is worse or lower than the same month of the preceding year; that this is the case becomes evident if it is considered that the point on the total curve for the current month is obtained by adding the actual value 80 for the current month to the preceding and subtracting the value for the same month of the previous year.

85 Attention is also directed to the fact that the total curve is an annual rate curve since it gives a definite comparison from year to year and as already pointed out, may be continued over a series of years with a plurality of cumulative curves used in conjunction therewith if desired.

90 On curves such as for example, payroll curves, special symbols or stars may be located at prominent peaks and valleys, and foot notes made in the margin of the cards to specify the cause, such as a holiday, inventory, shut down, etc.

95 In making the Z charts the total and cumulative value curves are drawn to the same scale and the same color may be used for both while the actual value curve alone 100 is drawn to a different scale and of a contrasting color.

Various methods of utilizing the invention may suggest themselves to those skilled in the art, and I intend only such limitations 105 as are indicated in the appended claims.

What I claim is:

1. A plurality of translucent sheets having variously colored curves thereon adapted to be compared by being superposed or overlapped, each sheet being provided with major coordinate lines which are correspondingly spaced on the several sheets and are adapted to register when the sheets are compared, and intermediate coordinate lines 110 which are non-correspondingly spaced on the several sheets but cooperate with the major coordinate lines on each sheet.

2. A plurality of translucent sheets having curves thereon representing values and adapted to be compared by being superposed or overlapped, each sheet being provided with major coordinate lines which are correspondingly spaced on the several sheets and are adapted to register when the sheets are 120 compared, and intermediate coordinate lines which are non-correspondingly spaced on the several sheets but equitably divide the spaces between the major coordinate lines on 125 each sheet.

3. A plurality of translucent sheets having curves thereon representing values and adapted to be compared by being superposed or overlapped, each sheet being provided with relatively heavy major coordinate lines which are correspondingly spaced on the several sheets and are adapted to register when the sheets are compared, and intermediate coordinate lines which are non-correspondingly spaced on the several sheets but equitably divide the spaces between the major coordinate lines on each sheet. 70
4. A plurality of translucent sheets having curves thereon representing values and adapted to be compared by being superposed or overlapped, each sheet being provided with relatively heavy major coordinate lines which are correspondingly spaced on the several sheets and are adapted to register when the sheets are compared, and relatively light intermediate coordinate lines which are non-correspondingly spaced on the several sheets but cooperate with the major coordinate lines on each sheet. 75
5. A plurality of translucent sheets having curves thereon representing values and adapted to be compared by being superposed or overlapped, each sheet being provided with major coordinate lines which are correspondingly spaced on the several sheets and are adapted to register when the sheets are compared, intermediate coordinate lines which are non-correspondingly spaced on the several sheets but equitably divide the spaces between the major coordinate lines on each sheet. 80
6. A plurality of translucent curve sheets adapted to be compared by being superposed or overlapped, each sheet being provided with major coordinate lines which are correspondingly spaced on the several sheets and are adapted to register when the sheets are compared, and intermediate coordinate lines of contrasting appearance which are non-correspondingly spaced on the several sheets but cooperate with the major coordinate lines on each sheet. 90
7. A series of coordinate sheets adapted to be superposed having major division lines spaced at a predetermined unit distant apart for purposes of comparison and having different intermediate division lines on different cards of the series. 95
8. A plurality of curve sheets adapted to be compared in which the sheets have correspondingly located zero lines and unlike but related curves, the scale for each curve being selected to cause the mean curve height to be at a predetermined fixed distance from the zero line on all the curve sheets. 105
9. A plurality of curve sheets adapted to be compared in which the sheets have corre- 110
- spondingly located zero lines and unlike but related curves, the scale for each curve being selected to cause the mean curves height to be the same distance from the zero line on all the curve sheets. 120
10. A curve sheet having a single base line and a common time scale in one direction, three curves,—one representing actual values for each period of time, a second representing cumulative values obtained by adding the values for each period to the preceding, and a third obtained by plotting the values for a time period equal to the total period represented on the sheet but reckoned backward for each point on the curve. 125
11. A curve sheet having a coordinate area divided into time periods in one direction and three curves plotted thereon with a common base line and representing respectively, actual values for each time period into which the coordinates divide the sheet; cumulative values obtained by adding the value of each time period to the preceding; and total values for a period equal to the total period represented on the sheet but measured backward from each point on the curve. 130
12. A curve sheet having a coordinate area with its base line divided into divisions to represent equal parts of a year and three curves plotted from said base line representing respectively first actual values for the several parts of a year into which the base is divided; second, cumulative values obtained by adding the value for each part of a year to the preceding total; and third, total values obtained by taking the value for the year preceding measured backward from each point on the curve. 135
13. A curve sheet having a coordinate area divided into time periods in one direction and three curves plotted thereon with a common base line and representing respectively, actual values for each time period, cumulative values obtained by adding the value of each time period to the preceding; and total values obtained by taking the total values for total periods each equal to the total period represented on the sheet but measured backward from each coordinate line of the page, the cumulative and total curves being plotted to smaller scales than the continuous value curve to bring them close to the continuous value curve. 140
14. A curve sheet having a coordinate area divided into time periods in one direction and three curves plotted thereon in different colors with a common base line and representing first actual values for each time period into which the coordinates divide the sheet; second, cumulative values obtained by adding the value of each time period to the preceding; and third, total values obtained by taking the total values for a total period each equal to the total period repre- 145

- 6
sented on the sheet but measured backward from each coordinate line of the page, and data figure columns for the several curves located in the margin of the sheet and corresponding in color to the curve to which they relate.
15. A curve sheet having a coordinate area divided into time periods in one direction and three curves plotted thereon with a common base line and representing first actual values for each time period into which the coordinates divide the sheet; second, cumulative values obtained by adding the value of each time period to the preceding; and third, total values obtained by taking the values for a total period, each equal to the total period represented on the sheet but measured backward from each coordinate line of the page, and data figure columns for the several curves bearing corresponding relative positions on the sheet to the curves to which they relate.
16. A curve sheet having a coordinate area with a base line divided into divisions to represent equal parts of a year and three curves plotted from said base line in contrasting colors and representing respectively first actual values for the several parts of a year into which the base is divided, second, cumulative values obtained by adding the value for each part of a year to the preceding total, and third, total values obtained by taking the value for one year at each part of a year measured backward therefrom, and columns of data figures located in the margin of the sheet corresponding in color to the curve to which they relate.
17. A curve sheet having a coordinate area and a base line divided into divisions to represent equal parts of a year and three curves plotted to different scales thereon from said base line representing respectively, first, actual values for the several parts of a year into which the base is divided; second, cumulative values obtained by adding the value for each part of a year to the preceding total, and third, total values obtained by taking the value for one year at each part of a year measuring backward therefrom, and columns of data figures bearing corresponding relative positions to the curves to which they relate.
18. A curve sheet having a coordinate area divided into time periods in one direction and three curves plotted thereon with a common base line and representing first actual values for each time period into which the coordinates divide the sheet; second, cumulative values obtained by adding the value of each time period to the preceding; and third, total values obtained by taking the values for a total period, each equal to the total period represented on the sheet but measured backward from each coordinate line of the area, and columns of data figures located opposite the points on the curves to which they relate, said columns bearing corresponding relative positions on the sheet to the curves to which they relate.
19. A plurality of curve sheets having base lines representing successive equal time intervals and adapted to be plotted correspondingly and overlapped in one direction to form a continuous curve and to be overlapped in one direction for seasonal comparisons, and numbers designating the year to which the record relates on opposite corners of each sheet, whereby it is visible when the sheets are overlapped either in one direction or the other.
20. A plurality of translucent curve sheets adapted to be superposed for comparison between curves for different years by months or seasons, having correspondingly located base lines, provided with short cross lines indicating months of the year and adapted to register, and dissimilarly arranged coordinate lines, and a curve on each sheet plotted to a scale to make it correspond in general position to those of the other sheets.
21. A plurality of translucent curve sheets adapted to be superposed for comparison between curves for different years by months or seasons, having correspondingly located base lines provided with means for indicating months of the year and adapted to register, and dissimilarly arranged coordinate lines, and a curve on each sheet plotted to a scale to make it correspond in general position to those of the other sheets.
22. A plurality of translucent curve sheets adapted to be superposed for comparison between curves for different years by months or seasons, having correspondingly located base lines provided with means for indicating the relation between the ends of the weeks and the ends of the months and adapted to register, and dissimilarly arranged coordinate lines, and a curve on each sheet plotted to a scale to make it correspond in general position to those of the other sheets.
23. A curve sheet having a coordinate area, a cumulative value curve plotted thereon to a predetermined scale for a series of time periods, and a total value curve plotted thereon to the same scale for time periods equal to the total period plotted on the cumulative value curve, with said curves approaching a common point.
24. A curve sheet having plotted thereon a cumulative value curve for a series of sub-periods of time forming parts of a predetermined time period, and a total value curve plotted to the same scale and based on a succession of overlapping time periods calculated backwardly for each sub-period.
25. A curve sheet having plotted thereon

a cumulative value curve and a total value curve to the same scale so that they approach a common point at the end.

26. A plurality of translucent curve sheets having dissimilar but related curves thereon, adapted to be superposed for comparison and a corresponding time scale to which each is plotted whereby the cards may be moved one over the other to bring the curves substantially into register, and the lead or lag between the curves read from the time scales.

27. A pair of translucent curve sheets having dissimilar curves thereon and adapted to be superposed for comparison, and a corresponding scale on each card to which the curves are plotted in one direction, and non-corresponding scales for the curves in the other direction, chosen to make the mean curve height of the different curves substantially alike.

28. A plurality of coordinate record cards having equally spaced major coordinate lines adapted to be arranged in alignment with the cards partially overlapped to make a continuous record, and intermediate coordinate lines of contrasting appearance and dividing the spaces between the major coordinate lines into unequal subdivisions on the several sheets.

29. A plurality of translucent curve sheets adapted to be superposed for comparison and each having a different but related curve plotted thereon, and a correspondingly located zero line for each curve, the scales to which the different curves are drawn being such as to make them correspond in general when the sheets are superposed.

30. A curve sheet having a coordinate area

divided into time periods in one direction, and two curves plotted thereon to the same scale with a common base line and representing first cumulative values obtained by adding the actual value of each time period of the preceding, and second, total values obtained by taking the values for any predetermined period, but each measured backwardly from its point on the curve.

31. A Z-chart comprising an actual value curve, a total value curve, and a cumulative value curve.

32. A Z-chart comprising an actual value curve, a total value curve, and a cumulative value curve, the actual value curve being drawn to contrast in appearance with the total and cumulative curves.

33. A Z-chart comprising an actual value curve, a total value curve, and a cumulative value curve, the curves being drawn to contrast in appearance.

34. A Z-chart comprising an actual value curve, a total value curve, and a cumulative value curve, the total and cumulative curves being drawn in one color and the actual value of the curve in another color.

35. A plurality of sheets overlapped in one direction with one pair of their edges in registering alignment, a base line, major coordinate lines parallel to the base similarly located on each sheet and unlike intermediate or subdivisional lines on the several sheets drawn to contrast in appearance, whereby unlike curves may be readily compared as to a common element represented, such as time.

In witness whereof, I have hereunto set my hand this 12 day of September, 1917.

WILLARD C. BRINTON.
